Application September 30, 1946, Serial No. 700,304

5 Claims. (Cl. 312—63.)

1

This invention relates to mechanical merchandising machines and more particularly to machines for vending packaged merchandise such as hosey, neckties, handkerchiefs and the like.

The principal object of the invention is to provide a medium through which staple, ready to use merchandise may be displayed for the benefit of and purchase by the public without necessity for personal salesmanship. The invention opens an avenue for sales of much needed merchandise at points remote from their normal source such as in hotel lobbies, train and bus depots, airports, and many other desirable locations yet where the required merchandise is not immediately available at popular prices.

Another object of the invention is to provide a merchandise vending machine in which the vending mechanism is housed in a cabinet, portions of which are embraced by a translucent outer covering of plastic or like material, concealing fluorescent tubes which afford vari-colored illumination, subdued by the translucent covering.

Still another object of the invention is to provide a simplified vending mechanism so designed and constructed that packages or boxes containing merchandise are singly and selectively propelled to a position of accessibility to a purchaser from the top of one of a plurality of parallel and superimposed columns. By virtue of such an arrangement, the merchandise is elevated to a point of discharge most convenient to the purchaser which requires no stooping or reaching, yet providing a comparatively large storage space for merchandise.

Yet another object of the invention is to provide a moving display atop the cabinet, containing merchandise representative of that stored in the machine and from which choice of articles are made by number or other identifying means, preparatory to actuating the machine to acquire the selected article, which is effected by operating a plunger bearing an identification corresponding to that on the display, after depositing into the machine a coin or coins of predetermined denominations and value.

With the foregoing and other objects in view the invention has further reference to certain features of accomplishment which will become apparent as the description proceeds taken in connection with the accompanying drawings wherein:

Figure 1 is a front perspective view of a machine constructed according to the present invention.

Figure 2 is an end view in vertical section, with portions broken away.

Figure 3 is a fragmentary rear perspective view of one of the vending units.

Figure 4 is a plan view of the arrangement as shown in Figure 3, and

2

Figure 5 is a side elevational view of the package discharging mechanism per se, at mid-position in its operating cycle.

Continuing with a more detailed description of the drawings, reference is primarily made to Figure 1, disclosing the cabinet and in which numeral 10 denotes a base on which is superimposed sections A and B which may be referred to hereinafter as upper and lower sections respectively, although the vending mechanism, as it will be presently learned, is identical in each section. At the bottom, top and midway between the top and bottom of the cabinet are strips of molding 11 which encircle the cabinet and are not only decorative but also serve as a mounting for a covering 12 of translucent material, such as Plexiglas or other plastic. Between this covering and the actual walls 13 of the machine are glass tubes 14, containing electrically excitable gases producing vari-colored illumination which is subdued by frosting the inner surface of the covering 12, or by other methods, rendering the covering translucent. Animation of this illumination may be simulated by alternately energizing the tubes.

The moldings 11 at the top and midsection of the cabinet are provided with elongated openings 15 extending substantially the width of the cabinet, each opening being embraced by a frame 16, disposed inwardly of the translucent cover or shell 12 to define a group of merchandise outlets each being covered by a flap 17 which are hinged along their tops at 18 (Fig. 2) to swing outwardly by cartons 19 of merchandise being thrust thereagainst in a manner to be presently explained. However, these flap closures discourage pilfering by preventing instruments from being surreptitiously thrust into the article magazines in efforts to withdraw cartons therefrom.

Superimposed upon the top of the upper section A of the cabinet is a merchandise display consisting primarily of a base 20, journaled in which are two vertical shafts 21, only one of which is shown. Mounted on these shafts adjacent the base 20 is an annularly grooved pulley 22 and adjacent the upper end of the shafts are mounted smaller pulleys 23. A belt 24 surrounds pulleys 22 while a belt 25 surrounds pulleys 23. Receptacles 26 and 27 are mounted on the belts 24 and 25, in the manner shown, to receive the lower and upper ends respectively of cartons 19 adapted to be open for displaying merchandise placed therein but not shown in the drawing. Obviously the difference in size of the pulleys 22 and 23 reduces the spacing of the leads of the belts, hence the cartons 19 will be slightly inclined from the vertical, a position most suited to the vision of one making a selection from merchandise displayed in the cartons 19. It is apparent that various mechanisms may be employed to cause

the pulleys 22 and 23 to revolve to move the merchandise slowly about the display, but for purposes of illustration, a small low speed motor 28 rotates the shaft 21 through the medium of a belt 29 engaging a pulley 30 mounted on the shaft 21.

The described display mechanism is enclosed in a housing 31 of transparent material whose walls are inclined in the manner shown and which is provided with an elongated top 32. A panel 33 may be provided and suitably illuminated to exhibit the character of merchandise contained in the machine; the manufacturer's trade-mark; instructions for operating the machine and other indicia.

Referring now to the mechanism for ejecting article containing cartons from the machine; it will be observed in Figures 2 and 3 that the cartons 19 are arranged in stacks or columns of which there are several in parallel relationship in both sections A and B. In order that the uppermost carton of each column may be ejected, it is necessary that the entire column be continuously urged upwardly. This is accomplished by a coil spring 34, one of which is disposed vertically at the rear of each vending unit, as shown in Figures 2 and 3, although the spring has been deleted from the lowermost unit shown in Figure 2. This spring 34 is anchored at 35 to a plate 36 and to its upper end is attached to the bight *a* of a small wire cable 37, the ends of the latter being anchored at *b* to the inverted V-shaped sides 38 of a carton supporting platform 39, after passing over small sheaves 40, appropriately arranged in the top of the magazine frame 41 to dispose its leads perpendicularly to the platform 39.

It is apparent that the cable 37 is under tension imposed by the spring 34 at all times to maintain an upward urge on the column of cartons 19 from the bottom, as long as there is a carton left on the platform 39. Each magazine is filled from the top, the cartons being placed one upon the other as the platform 39 is lowered and the spring 34 expands. The upward pull upon the column, being centralized by attaching the cable ends to the inverted V-shaped sides of the frame, the cartons are maintained in a horizontal plane and the uppermost carton is always in readiness for ejection through the opening 42 at the top of the front wall of the magazine.

The carton ejecting mechanism consists of an arm 43 which is oscillatably mounted on a rod 44 which extends the full width of the machine to accommodate similar arms in adjacent magazines on the same plane. To the forward end of arm 43 is attached a plate 45 at right angles thereto which normally covers the opening 42 through which cartons are ejected. Thus it serves as an auxiliary to the flap door 17 to preclude pilfering of cartons from the machine.

The opposite end of the arm 43 has a lobe 46 to which is pivoted at *c*, one end of a carriage 47, supported by a roller 48 which bears upon the uppermost carton 19 before and during its ejection and subsequently, upon the next succeeding carton, as exemplified in the lower portion of Figure 2.

Complementary to the arm 43 and carriage 47 is a lever 49, rockably suspended on a transverse rod 50 which likewise extends the full width of the machine to similarly support analogous levers in adjacent magazines. The forward end of the lever 49 is curved at 51 and before and during the ejecting operation bears upon the tail

of a detent 52, pivoted at *d* to the carriage 47. The forward end of the detent 52 enters a recess 53 in the periphery of the lobe 46 of the arm 43 to lock the latter against premature displacement. A spring 54 connects the detent 52 and carriage 47 in a manner to return the detent to engaged position with the recess 53 when displaced.

To actuate the described mechanism, a solenoid 55 is mounted on the plate 36 rearwardly of the magazine whose plunger 56 is pivoted at *e* to the lower end of a curved arm 57, the latter being pivoted at *f* to the magazine frame, which pivotal point, it will be observed, is located close to the solenoid to insure adequate displacement of the upper end of arm 57. Immediately above the pivot point *f*, parallel guides 58 are mounted to restrict lateral movement of the arm, yet allows ready withdrawal thereof from the rear when filling the magazines with cartons in the manner to be presently explained.

Slidably disposed on the top of the uppermost carton 19 is a shoe 59, disposed parallel with and under the tail portion of the lever 49, which, as apparent in Figures 3 and 4, is looped at 60 to receive the upper end of the curved arm 57. The shoe 59 is bifurcated at 61 to embrace the curved arm 57, to which it is pivoted, as shown. A rounded protuberance 62 is formed transversely across the upper face of the shoe 59 to engage a roller 63 carried by the arm 49 approximately midway of its ends. Moreover, the shoe 59 has affixed transversely to its underside a bar 64 whose function is to bear against the rear end of the uppermost carton 19 and thrust the same towards the front of the cabinet and partially through the discharge opening 15 thereof, in the manner shown in Figure 2 in section B.

To fill the magazine with cartons containing merchandise, the pin serving to pivotally attach the shoe 59 to the curved arm 57 is removed and the arm may be released from the loop 60 of arm 49 by simply lifting the latter. The pivot pin *e* of the solenoid plunger is removed, allowing the arm 57 to be moved downwardly. Cartons then may be passed endwise into the magazine and onto the platform 39, by virtue of the cut-away portions 65 (Fig. 3) in the rear vertical members of the magazine frame 41. After replenishing a depleted magazine, the arm 57 is restored to its original operative position.

In operation, an article of merchandise is first chosen from the display and a coin or coins of predetermined value are deposited into the chute 66 (Fig. 1). A plunger 67, properly identified with the articles of merchandise displayed, is selected according to identification and is pressed inwardly, which operation energizes the solenoid 55 of the magazine with which the plunger is associated.

Upon energization of the magnet 55, plunger 56 is attracted inwardly to actuate the curved arm 57 on its pivot *f*. The upper end of the arm will move inwardly to a certain extent without displacing arm 49 because of the freedom permitted by the loop 60 in the tail portion thereof. However, shoe 59 is advanced thereby, bringing its plate 64 against the rear end of the uppermost carton 19, thrusting the same outwardly through the discharge opening 42 and into a position of accessibility to the operator of the machine. However, when the shoe 59 is advanced to a position to engage its protuberance 62 with the roller 63 of lever 49, which occurs just prior to

ejection of the carton, the rear portion of the lever 49 is elevated, causing the curved forward end 51 to come to bear on the tail of the detent 52, raising its forward end out of locking engagement with the recess 53 in the lobe 46 of arm 43. The arm is then released to the action of a spring 68 which elevated the same, raising the plate 45 carried thereby, out of the path of the carton being ejected.

Upon deenergization of magnet 55, which takes place immediately after completion of the foregoing operation, a spring 69, which bears against the curved arm 57, returns the latter to its original starting position, bringing with it the shoe 59, whose forward end rides off the rear end of the ejected carton to resume a renewed position on the carton next below.

After the patron withdraws from the machine the carton partially protruding therefrom, action of the loading spring 34 causes the next succeeding carton to move into vending position as the column is moved upwardly. The top carton will engage the roller 48 of the carriage 41, moving it from the position shown in the lower portion of Figure 2 to that shown in the upper position thereof. This operation will automatically cause the arm 43 to resume operative position and the detent, in like manner will resume interlocked relationship with the recess 53 in the lobe 46 of the arm 43. Lever 49 will be in a position whereby its curved end will again bear upon the tail of the detent to actuate the same upon renewed operation of the machine.

The coin controlled mechanism including various electrical circuits for energizing the solenoids 55 of the several merchandise magazines, has been deleted from the disclosure since these features are conventional and are not necessarily a part of the invention.

Manifestly, the construction as shown and described is capable of some modification and such modification as may be construed to fall within the scope and meaning of the appended claims is also considered to be within the spirit and intent of the invention.

What is claimed is:

1. In a merchandise vending machine, a vending mechanism including a magazine for article containing cartons, said magazine having a carton discharge opening at its top, a pivotally displaceable arm carrying a plate on one end normally closing said opening, means exerting a continuous upward force on the bottom of the column of cartons in each of said magazines, a second arm rearwardly of said magazine pivoted to oscillate in a vertical plane, a shoe pivoted to said arm and slidable on the uppermost carton in said magazine and having a protuberance thereon, a lever pivoted intermediate its ends having a roller engageable with the protuberance on said shoe, an electro-magnet for actuating said second lever and said shoe, means carried by said shoe for exerting a force against the rear of the uppermost of the cartons in said magazine in a direction towards the discharge opening thereof and means intermediate said first arm and said lever and actuated by the latter to simultaneously displace said closing plate to dispose said carton in a position of accessibility exteriorly of said cabinet.

2. In a merchandise vending machine, a vending mechanism including a carton containing magazine having a carton discharge opening at the top thereof, a pivotally displaceable arm carrying a closure for said opening, means for

exerting a continuous upward force against the bottom of the column of cartons in said magazine to dispose the uppermost carton in said column in a position for discharge through said opening, a second arm pivotally mounted rearwardly of said magazine, a shoe connected to said latter arm for sliding displacement on the uppermost of said cartons and having means thereon for exerting a forward thrust on the rear of said uppermost carton, electro-magnetic means for actuating said second arm and means actuated by said shoe to effect operation of said first arm to displace said magazine discharge closure.

3. A merchandise vending mechanism including a magazine containing merchandise filled cartons, said magazine having a carton discharge opening at its top, an arm oscillatable on a horizontal axis above the uppermost carton in said magazine and having thereon a closure for said opening, means for elevating the column of cartons to dispose the uppermost thereof in position for discharge through said opening, a lever pivoted rearwardly of said arm adapted to actuate said arm, a second arm pivoted rearwardly of said magazine, a shoe connected to said second arm having means thereon for actuating said lever, means also carried by said shoe for exerting an expelling force on the uppermost carton and electro-magnetically operated means for actuating said second arm to operate said first arm and said shoe for simultaneously opening said closure and for expelling said uppermost carton.

4. A merchandise vending mechanism including a magazine having a discharge opening at its upper end, a closure for said opening, a column of merchandise containing cartons in each of said magazines, a pivoted arm above said column for displacing said closure, means yieldingly supporting the column of cartons in said magazine to dispose the uppermost carton opposite said discharge opening, a shoe slidable on said uppermost carton, means actuated by said shoe for operating said pivoted arm, means also carried by said shoe for ejecting said uppermost carton through said opening and electro-magnetic means for operating said shoe.

5. In a machine for vending merchandise containing cartons, a vending mechanism including a carton containing magazine having a discharge opening at its top, a closure therefor, a pivoted arm for displacing said closure, means for imposing a constant upward thrust on the lowermost of the cartons in said magazine to dispose the uppermost carton for ejection through said opening, a slidable shoe, means actuated by said shoe to operate said pivoted arm for displacing said closure, means carried by said shoe for ejecting said uppermost carton through said opening, electro-magnetic means for actuating said shoe and means for reestablishing said closure and shoe in operative positions upon de-energization of said electro-magnetic means.
